(57) **CLAIM**

I claim the ornamental design for an insulated pot wrap, as shown and described.

DESCRIPTION

FIG. 1 is a perspective view of the insulated pot wrap of the present invention in position about a pot.

FIG. 2 is a left side plan view of the insulated pot wrap in position about a pot.

FIG. 3 is a top plan view of the insulated pot wrap in position about a pot.

FIG. 4 is a front plan view of the insulated pot wrap in position about a pot.

FIG. 5 is a rear plan view of the insulated pot wrap in position about a pot.

FIG. 6 is a right side plan view of the insulated pot wrap in position about a pot.

FIG. 7 is a bottom plan view of the insulated pot wrap in position about a pot.

FIG. 8 is a perspective view of the insulated pot wrap preparatory to wrapping about a pot.

FIG. 9 is a top plan view of the insulated pot wrap of the present invention.

FIG. 10 is a side elevation of the view of FIG. 9.

FIG. 11 is a bottom plan view of the insulated pot wrap of the present invention.

FIG. 12 is a side elevation of the view of FIG. 11.

FIG. 13 is an end elevation view of the bifurcated end of the insulated pot wrap of the present invention.

FIG. 14 is an end elevation view of the opposite end of the insulated pot wrap of the present invention; and,

FIG. 15 is a perspective view of a second embodiment of the insulated pot wrap of the present invention having a quilted outer texture in position about a pot
